UNITED STATES PATENT OFFICE.

WILLIAM J. MOXLEY, OF CHICAGO, ILLINOIS.

DESIGN FOR A BUTTER OR OLEOMARGARIN PRINT OR BRICK.

SPECIFICATION forming part of Design No. 32,780, dated June 5, 1900.

Application filed May 9, 1900. Serial No. 16,093. Term of patent 14 years.

To all whom it may concern:

Be it known that I, WILLIAM J. MOXLEY, a citizen of the United States, residing at Chicago, Illinois, have invented and produced a new and useful Design for Butter or Oleomargarin Bricks or Prints, of which the following is a specification.

In the drawings, Figure 1 represents a plan view of a butter-print, and Fig. 2 represents a central longitudinal section of the same.

As shown in the drawings, the leading or important feature of my design consists in a butter or oleomargarin brick or print having on its upper or top surface a series of ridges

or beads A, arranged transversely of the brick 15 or print and surrounded by a molding broken into separate raised sections. The moldings divide the brick into two panels, each of which contains a series of the beads surrounded by a line of molding.

What I regard as new, and desire to secure by Letters Patent, is—

The design for a butter or oleomargarin print or brick herein shown and described.

WILLIAM J. MOXLEY.
